MEASURING TAPE REEL HOUSING
CONSTRUCTIONFrank J. Mortimer, Blue Point, N. Y., assignor to
Justus Roe & Sons, Patchogue, N. Y.

Application January 31, 1948, Serial No. 5,535

4 Claims. (Cl. 242—84.8)

1

This invention relates to an improved measuring tape reel housing construction and, more particularly, to a central rotary winding reel for measuring tape housings of the enclosed type.

It is an object of the invention to provide a tape reel having a retractable handle arm pivoted externally thereto and swingable from an operative, extended winding position to a retracted inoperative position of reduced compass.

A further object of the invention is the provision of a tape reel of the character indicated wherein the head or handle portion of the handle arm may be received through an aperture in the outer face of said reel to be unobtrusively disposed in the retracted, inoperative position of said handle arm.

Another object of the invention is the provision of a tape reel of the character indicated having simple and effective yieldable means for releasably retaining the handle portion of the retractable pivoted handle arm in the inoperative position thereof.

An additional object of the invention is the provision of a tape reel having an axial hub to which the measuring tape may be secured by means of a clamping element or collar, said clamping element or collar serving additionally to releasably retain the handle portion of the pivoted handle arm, as by means of an integral resilient tongue projecting outwardly for engagement against said handle portion.

A further object of the invention is the provision of a tape reel of the character indicated which may be fabricated easily and inexpensively from a minimum of parts assembled to a unit of rugged construction.

The foregoing objects as well as additional objects and advantages of the invention will be readily apparent in the course of the following detailed description taken in connection with the accompanying drawing which illustrates a preferred embodiment of the invention, and wherein:

Fig. 1 is a front elevation of a measuring tape housing incorporating the tape winding reel of the invention and showing the foldable handle arm in inoperative position;

Fig. 2 is a side elevation of the housing;

Fig. 3 is a perspective view of the tape reel with the foldable handle arm in extended operative position;

Fig. 4 is a view similar to Fig. 1 but with a portion of the housing broken away to expose the coiled tape therewithin and with the handle arm in extended operative position;

2

Fig. 5 is a fragmentary detail view of the assembled tape reel as seen from inside the housing with the measuring tape partially coiled on the winding flange of the tape reel;

Fig. 6 is a fragmentary detail view of the assembled tape reel as seen from the outside of the housing, the handle arm being in extended operative position and the resilient handle-retaining tongue being visible through the aperture in the outer face of the tape reel;

Fig. 7 is a top plan view, part of the tape housing being broken away, showing the disposition of the tape reel with respect to the housing.

Referring now to the drawing in greater detail, the tape reel 10 may be formed in any suitable manner, as by die-casting, and is preferably cylindrical in shape having a circular base 11 and an annular winding flange 12 formed in such a manner as to define a peripheral mounting flange 11a extending outwardly from said annular flange. An axial hub 13 is formed integrally with tape reel 10 and said hub may be internally threaded in order to mount the reel on the cylindrical housing H. Hub 13 serves additionally for fastening the measuring tape 14 to the tape reel 10, as will be more fully described hereinafter.

Tape reel 10 is further provided with a pair of integral bearing recesses 15 communicating with a slot (not shown) extending therebetween in order to pivotally retain a handle arm 16 rolled over upon itself at one end, as at 17, for the reception of a pivot pin 18. Handle arm 16 may be conveniently pivoted externally of circular base 11 by swaging the material of the base over the ends of pivot pin 18, as shown at 19 in Fig. 5, or in any other desired manner.

A handle or knob 20 is rotatably mounted adjacent the free end of handle arm 16, said handle preferably terminating in a spherical or bulbous protrusion 20a for a purpose to be indicated. An aperture 21 is formed in base 11 diametrically opposite the pair of bearing recesses 15 in order to receive the handle 20, thereby allowing the handle arm 16 to be swung from its extended operative position of Figs. 3, 4, 6 and 7 to its retracted inoperative position clearly illustrated in Fig. 1.

The measuring tape 14, may be secured to the hub 13 of reel 10 by means of a clamping member or collar 22 frictionally engaged about said hub, the free end of said tape being held between the ends of said clamping member as by a grommet or rivet 23.

Tape 14 is extended to be wound externally

of annular winding flange 12 through a slot 24 in said flange. A resilient tongue or retaining member 25 is struck from the body of the clamping member 22 and extends outwardly therefrom a sufficient distance to releasably engage the handle or knob 20 of handle arm 16 when said handle or knob is inserted within aperture 21 in the inoperative position of Fig. 1. As has been previously indicated, handle 20 preferably terminates in a spherical or bulbous protrusion 20a so that said handle will be yieldably held by retaining member 25 until it is desired to lift the handle and swing arm 16 to its operative, extended position in which position said handle may be easily grasped for manual manipulation of the winding reel 10.

It will thus be noted that a dual purpose is achieved in the reel of the present invention through the agency of a single element. More specifically, clamping member 22 serves not only to retain the end of measuring tape 14 but the integral resilient tongue 25 struck from said clamping member serves as a yieldable means for retaining the winding handle 20 and arm 16 in retracted inoperative position until required for rewinding the previously extended tape. In actual use the handle arm 16 may be lifted from retracted position quite satisfactorily with the finger tip or finger nail but, if desired, small lifting lugs or projectors 26 adjacent handle 20 may be employed.

Since certain additional modifications may be made in the tape reel of the present invention without departing from the scope thereof, it is intended that all matter contained in the foregoing specification and shown in the accompanying drawing be interpreted merely as illustrative and not in a limiting sense.

I claim:

1. A rotary winding reel for measuring tape housings, said tape reel comprising a circular base, an annular winding flange formed integrally with said base, an arm pivoted externally of said base adjacent one end thereof, a handle element fixed to the free end of said arm, said circular base being apertured for the reception of said handle element in the folded position of said arm, an integral hub extending inwardly of said base and centrally of said winding flange, and a clamping member fixed to said hub and serving to retain the inner end of the measuring tape, said clamping member having integral yieldable means projecting outwardly therefrom, whereby to releasably engage said handle element in the folded position of said arm and to allow manual engagement of said handle element in the extended position of said arm.

2. A rotary winding reel for measuring tape housings, said tape reel comprising a circular base,

an annular upstanding winding flange formed integrally with said base and spaced inwardly from the perimeter of said base to define a peripheral mounting flange, an arm pivoted adjacent one end of said base on the side opposite said winding flange, a handle element fixed to the free end of said arm, said base being apertured for the reception of said handle element in the folded position of said arm, an integral hub 10 extending inwardly of said base and centrally of said winding flange, and a unitary clamping member frictionally engaged about said hub and serving to retain the inner end of the measuring tape, said unitary member having yieldable means 15 projecting outwardly thereof, whereby to releasably engage said handle element in the folded position of said arm and to allow manual engagement of said element in the extended position of said arm.

3. A rotary winding reel for measuring tape housings, said tape reel comprising a circular base, an annular winding flange formed integrally with said base, an arm pivoted externally of said base adjacent one end thereof, a handle element rotatably mounted adjacent the free end of said arm, said circular base being apertured for the reception of said handle element in the folded position of said arm, an integral hub extending inwardly of said base and centrally of said winding flange, and a clamping member engaged about said hub and serving to retain the inner end of the measuring tape, said clamping member having an integral resilient tongue struck outwardly therefrom, whereby to releasably engage said handle element in the folded position of said arm and to allow manual engagement of said handle element in the extended position of said arm.

4. A rotary winding reel for measuring tape housings, said tape reel comprising a circular base, an annular winding flange formed integrally with said base, an arm pivoted externally of said base adjacent one end thereof, a handle element rotatably mounted adjacent the free end of said arm, said circular base being apertured for the reception of said handle element in the folded position of said arm, an integral hub extending inwardly of said base and centrally of said winding flange, and a clamping member engaged about said hub and serving to retain the inner end of the measuring tape, said clamping member having an integral resilient tongue struck outwardly therefrom, said handle element terminating in a bulbous protrusion yieldably engageable by said resilient tongue, whereby to releasably engage the bulbous protrusion of said handle element in the folded position of said arm and to allow manual engagement of said bulbous protrusion in the extended position of said arm.

FRANK J. MORTIMER.
